UNITED STATES PATENT OFFICE.

GEORGE A. LUCKE, OF BALTIMORE, MARYLAND, ASSIGNOR OF ONE-THIRD TO
FREDERICK CLEMENT WEBER, OF BALTIMORE, MARYLAND.

STOPPER FOR LAVATORY-FIXTURES.

1,195,827.

Specification of Letters Patent. Patented Aug. 22, 1916.

Application filed March 7, 1916. Serial No. 82,738.

To all whom it may concern:

Be it known that I, GEORGE A. LUCKE, a citizen of the United States, residing at Baltimore, in the State of Maryland, have 5 invented new and useful Improvements in Stoppers for Lavatory-Fixtures, of which the following is a specification.

The invention relates to a stopper, and more particularly to the class of stoppers 10 for use in basins, bath tubs or other like lavatory fixtures.

The primary object of the invention is the provision of a stopper of this character wherein the construction thereof is novel 15 in form so that it may be conveniently applied to the waste opening in a bath tub, wash basin or the like with despatch, and will serve to close the said opening without the use of the ordinary rubber stopper or the 20 like and thereby dispensing with the chain connected with such stoppers.

Another object of the invention is the provision of a stopper of this character which is in the form of a shutter and is de- 25 signed to close the waste opening in the wash bowl or basin, the shutter being readily adjustable by hand so that the opening can be closed and opened at will.

A further object of the invention is the 30 provision of a stopper of this character wherein the parts are assembled in a novel and unique manner so as to assure the positive closing of the waste port or opening without possibility of leakage, the stopper 35 being made from a minimum number of parts and can be readily attached and detached from the waste port or opening.

A still further object of the invention is the provision of a stopper of this character 40 wherein wear thereon is reduced to a minimum and the possibility of the stopper becoming defective is eliminated.

A still further object of the invention is the provision of a stopper of this character 45 which is extremely simple in construction, thoroughly reliable in operation, strong, durable and inexpensive of manufacture.

Other objects will be in part obvious and in part hereinafter pointed out.

50 The invention accordingly consists in the features of construction, combination of elements and arrangement of parts which will be exemplified in the construction hereinafter described, and the scope of the applica-

tion of which will be defined in the appended claim. 55

In the accompanying drawings: Figure 1 is a top plan view of a stopper constructed in accordance with the invention; Fig. 2 is a fragmentary vertical sectional view 60 through a bath tub at the waste port or opening therein showing a stopper applied; Fig. 3 is a perspective view of the shutter; Fig. 4 is a perspective view of the attaching member, one part thereof being partly 65 broken away; Fig. 5 is a perspective view of the base ring or collar.

Similar reference characters indicate corresponding parts throughout the several views of the drawing. 70

Referring to the drawings in detail, A designates a portion of the bath tub, and B the waste port or opening therein, which has arranged within the same the usual guard C which is formed with the crossed 75 arm spider D, as usual, and into this guard is adapted to be inserted the ordinary resilient or other stopper which, in the use of the present invention, is dispensed with as well as the chain carrying the same. It is 80 of course understood that the portion of the bath tub is shown merely to illustrate the application and manner of use of the stopper hereinafter fully described, as said stopper is designed for use in wash basins or 85 other like lavatory fixtures.

The stopper comprises a base ring or collar 10 which is of the required size to snugly fit within the guard C permanently mounted within the waste opening or port. The ring 90 or collar 10 is formed with an annular flange 11 which is outturned therefrom to be disposed concentrically of the opening or port and has engaged with the outer edge thereof the clenched rim 12 of a convexed or semi-spherical shaped cap or shell 13 so that it forms a permanent part of the ring or collar 10 and is provided centrally thereof with an aperture 14 while concentrically of the latter is a series of spaced radially disposed substantially segment shaped openings 15 through which is adapted to flow 95 water from the bath tub to the waste pipe. 100

Within the cap or shell 13 is a cut-off shutter 16 which is correspondingly shaped 105 to the said cap or shell and is held therein for limited rotation, the shutter being formed with a central aperture 17, and also

with a plurality of radially disposed segment shaped openings 18 which are adapted to register with the openings 15 in the cap or shell when the water is to be drained or let out of the tub. The non-perforate portion 19 between the openings 18 in the shutter 16 is adapted to close the openings 15 in the cap or shell 13 when the water within the tub is to be shut off from the waste pipe.

Beyond the outer end of one of the openings 15 in the cap or shell 13 is a slot 20 through which is projected a thumb-engaging gear 21 integrally formed with the shutter 16 so that the latter can be partly rotated for the opening or closing of the waste port or opening in the tub, as will be clearly apparent.

Passed through the spertures 14 and 17 in the shell 13 and shutter 16, respectively, is the attaching member which comprises a screw 22 and a hook 23, the latter being formed with an internally threaded shank 24 for the adjustable engagement of the screw 22 therein, and this hook 23 engages the crossed arm spider D in the guard mounted in the waste opening or port and in this manner the stopper is fastened in place.

Surrounding the ring or collar 10 is a resilient gasket or washer 25 which serves to effect a fluid-tight joint between the stopper and the guard.

From the foregoing description, taken in connection with the accompanying drawings, the construction and manner of use of

my invention will be readily apparent and therefore, a more extended explanation has been omitted.

Having thus described my invention, I claim:

The combination with a waste pipe and a guard mounted therein spaced from the entrance end of said waste pipe, of a stopper having a ring adapted to telescope within the entrance end of the waste pipe and provided with an annular outwardly bent flange at its upper edge, a semi-spherical shaped shell having a rim bent about the flange and fast thereto, a shutter interiorly of and correspondingly shaped to the shell for opening and closing the same, said shutter resting upon the flange, a gasket concentrically of the ring and resting against the flange to form a fluid-tight joint between the entrance end of the waste pipe and said stopper, a stem having a hook end and an opposite internally threaded socket end, said hook end being detachably engaged with the guard, and a screw passed through the central opening in the shell and also centrally through the shutter and adjustably engaged in the internally threaded socket end of the stem, said screw having its outer free end flush with the outer surface of the shell.

In testimony whereof I affix my signature in presence of a witness.

GEORGE A. LUCKE.

Witness:

BENNETT S. JONES.
